(57) **CLAIM**

The ornamental design for a solar power bank and charger, as shown and described.

DESCRIPTION

FIG. 1 is a perspective view of a solar power bank and charger in a closed configuration;

FIG. 2 is a front view of the solar power bank and charger of FIG. 1;

FIG. 3 is a bottom view of the solar power bank and charger of FIG. 1;

FIG. 4 is a left-side view of the solar power bank and charger of FIG. 1;

FIG. 5 is a right-side view of the solar power bank and charger of FIG. 1;

FIG. 6 is a top view of the solar power bank and charger of FIG. 1;

FIG. 7 is a rear view of the solar power bank and charger of FIG. 1;

FIG. 8 is a perspective view of the solar power bank and charger of FIG. 1 in an open configuration;

FIG. 9 is a front view of the solar power bank and charger of FIG. 8;

FIG. 10 is a bottom view of the solar power bank and charger of FIG. 8;

FIG. 11 is a left-side view of the solar power bank and charger of FIG. 8;

FIG. 12 is a right-side view of the solar power bank and charger of FIG. 8;

FIG. 13 is a top view of the solar power bank and charger of FIG. 8; and,

FIG. 14 is a rear view of the solar power bank and charger of FIG. 8.

The broken lines shown in the drawings represent portions of the solar power bank and charger that form no part of the claimed design.

1 Claim, 8 Drawing Sheets
